UNITED STATES PATENT OFFICE.

WALTER K. FREEMAN, OF BROOKLYN, NEW YORK, ASSIGNOR TO WILLIAM S. HADAWAY, JR., TRUSTEE, OF BOSTON, MASSACHUSETTS.

REGULATOR FOR DYNAMO-ELECTRIC MACHINES.

SPECIFICATION forming part of Letters Patent No. 441,794, dated December 2, 1890.

Application filed September 20, 1890. Serial No. 365,677. (No model.)

To all whom it may concern:

Be it known that I, WALTER K. FREEMAN, a citizen of the United States, and a resident of Brooklyn, in the county of Kings and State of New York, have invented certain new and useful Improvements in Regulators for Dynamo-Electric Machines; and I do hereby declare the following to be a full and an exact description of the invention, which will enable others skilled in the art to which it appertains to make and use the same.

My invention relates particularly to that class of dynamo-electric machines in which an auxiliary dynamo or exciter is employed to charge the field-magnets of the main machine. In some of its features it is applicable to dynamos of various forms.

My invention consists in the novel construction of the field-magnets of a dynamo and in the means for adjusting the same relatively to the armature, whereby the current developed is enabled to be regulated and controlled by mechanical means.

My invention further consists in certain improved details of construction, relating particularly to the manner of connecting the field-magnets of the exciter with the frame of the main machine, all as will be fully described hereinafter.

In the accompanying drawings, Figure 1 represents a perspective view of the auxiliary dynamo or exciter of a dynamo-electric machine, showing a portion of the main frame of the latter, its main shaft, upon which the armature of the exciter is mounted, and the bearings for said shaft. Fig. 2 is an end elevation of the exciter, showing particularly the form and construction of the pole-extensions of the field-magnets and the devices for effecting the adjustment thereof. Fig. 3 is a bottom plan view of the same. Fig. 4 is a perspective view of a dynamo to which my regulating devices are applied.

Similar letters of reference in the several figures indicate the same parts.

Referring particularly to Fig. 1, A represents the shaft of the main dynamo; B, a portion of the frame of said machine, and C one of the bearings on said frame in which the main shaft is journaled.

D are the coils of the field-magnet of the

exciter; E, the cores thereof; F F, the core-extensions, and G the armature, whose shaft is connected to and driven by the shaft of the main machine.

The cores E E are rigidly secured to the frame-work B of the main machine by bolts or otherwise, and upon their reduced outer ends are mounted the arms or core-extensions F F. These extensions are applied so as to be capable of being turned or rotated upon the cores E E, and are made tapering and curved, so as to conform generally to the contour of the armature G, inclosed or partially inclosed by them.

To the extremities of the poles E E is secured by suitable bolts H H a bracket I or support, having an upwardly-extending arm I', which serves to support the outer bearings J of the armature-shaft, and having also a downwardly-extending arm or lug I², as shown in Figs. 2 and 3.

Lugs F' F' are formed upon the lower portions of the pole-extensions F F, as shown in Fig. 3. These lugs F' F' have secured to them eyebolts K K', whose eyes are provided, respectively, with right and left hand internal screw-threads, with which co-operate right and left screw-threads L' L² on an adjusting-shaft L, as shown. Said adjusting-shaft passes through an opening in the downwardly-projecting lug I², Figs. 2 and 3, and is provided with nuts or collars M M on opposite sides of said lug, whereby it is enabled to be freely rotated and yet have no longitudinal movement. A hand-wheel N, applied to the end of the shaft, enables it to be turned with ease in either direction.

From the described construction it is apparent that by manipulating the hand-wheel N the shaft L can be rotated and the pole-extensions F caused to simultaneously approach or recede from the armature G, and thus by varying the magnetic field of force cause a current of greater or less strength to be developed. In the adjustment of these pole-extensions it will be noted that it is principally the outer and narrower portions of them that are caused to approach or recede from the armature, the greater body of metal near the bases or pivotal points remaining at all times in such effective proximity to the armature as

to prevent destructive sparking and other injurious effects.

With pole-extensions constructed and adjusted in accordance with my invention the strength of current developed by the exciter, and consequently the current of the main machine, is enabled to be regulated and controlled promptly and to the greatest nicety.

The connection of the exciter to the main dynamo in the manner described renders the machine as a whole simple, strong, compact, and efficient.

In Fig. 4 a dynamo is shown to which my regulating devices are applied, the current generated being regulated to a fractional part of a unit without changing the speed of the armature or introducing any resistance in the field or shunt circuit.

Having thus described my invention, what I claim as new is—

1. In a dynamo-electric machine, the combination, with the armature and field-magnets, of the pole-pieces pivotally mounted on the ends of said magnets and having the lugs or projections F F', the eyebolts journaled in said lugs, and the right-and-left-hand screw-shaft co-operating with said eyebolts to vary the position of the pole-pieces simultaneously with relation to the armature, substantially as described.

2. In a dynamo-electric machine, the combination, with the field-magnets and the pole-pieces surrounding and movably mounted on the ends thereof, of the bracket secured on the ends of the magnets to retain the pole-pieces in position, and means, substantially as described, for adjusting said pole-pieces with relation to the armature, substantially as described.

3. In a dynamo-machine, the combination of the cores of the field-magnets, the bracket

screwed to the end of said cores, having the downwardly-extending lug for receiving the screw-shaft, the pivoted pole extensions, and the screw-shaft and its hand-wheel, substantially as described.

4. In a dynamo-machine, the combination of the armature, the field-magnets having the pivoted pole-extensions, the bracket on the ends of the cores, having the upwardly-extending supporting-arm and the downwardly-extending lug, and the adjustable screw-shaft and its hand-wheel, substantially as described.

5. The combination, with the frame of the main dynamo-machine and the shaft of said main machine, of the field-magnets, the auxiliary dynamo or exciter connected to and supported by said main frame, the adjustable pole-extensions of said exciter, and the armature thereof, connected to the shaft of the main machine, substantially as described.

6. The combination, with the frame of the main machine and the shaft of said machine, of the field-magnets of said machine, the field-magnets, the exciter connected to and supported by said main frame, the adjustable pole-extensions of said exciter, the bracket on the end of the core of the field-magnets, the armature, and the adjustable right-and-left screw-shaft, substantially as described.

7. In the herein - described dynamo, the bracket I, adapted to be secured to the ends of the cores of the field-magnets, and having the upper arm I' for supporting the armature-shaft, and the lower arm or lug I² for receiving the adjustable right-and-left screw-shaft, substantially as described.

WALTER K. FREEMAN.
